UNITED STATES PATENT OFFICE

LEWIS A. ETCHISON, OF CANA, NORTH CAROLINA, ASSIGNOR, BY DIRECT AND MESNE ASSIGNMENTS, OF SIX-TENTHS TO JACK GOBBEL AND THREE-TENTHS TO ADAM L. NEELY, BOTH OF MOCKSVILLE, NORTH CAROLINA, AND ONE-TENTH TO N. C. GRUBBS, OF FORSYTHE COUNTY, NORTH CAROLINA

PLANT SETTER

Refiled for abandoned application Serial No. 239,521, filed December 12, 1927. This application filed January 24, 1930. Serial No. 423,229.

The invention relates to devices for use in setting plants in the ground, and it is intended primarily for setting tobacco plants, although not restricted to this particular field of use.

It is the principal object of the invention to provide a simple, light and compact, hand-operated device, in which a plurality of means such as hole-forming means, hole-watering means and hole-closing means, are selectively operable under the influence of a single operating handle movable in different ways, instead of requiring separate handles as customary.

A hand-operated plunger is used as means for forming the plant-receiving hole in the earth, and another of my objects is to provide novel means whereby movement of this plunger may be utilized to operate the means for closing the hole around the roots of the plant received in said hole.

Yet another aim is to provide a construction in which the plunger contains water held in check by a valve, which valve may be opened by movement of said plunger in a predetermined manner, to discharge a desired quantity of water into the hole.

With the foregoing and minor objects in view, the invention resides in the novel subject matter hereinafter described and claimed, description being accomplished by reference to the accompanying drawings.

Fig. 1 is a side elevation partly broken away and in section, showing the relation of parts which exists when the device is being moved, after setting one plant, to the point at which the next plant is to be set, or when the hole-closing means is to be operated.

Fig. 2 is a side elevation partly broken away and in section showing the plunger depressed to form a plant-receiving hole in the earth.

Fig. 3 is a side elevation partly broken away and in section, at right angles to Fig.

1 and showing the parts in the same relative positions.

Fig. 4 is a vertical longitudinal sectional view with the parts related as in Fig. 2.

Fig. 5 is a view similar to Fig. 4 but showing the relation of parts which exists when the water valve is opened.

Fig. 6 is a side elevation partly broken away and in section, similar to Fig. 1, but showing the manner in which depression of the plunger operates the hole-closing means.

Fig. 7 is a horizontal sectional view on line 7—7 of Fig. 4.

Fig. 8 is a vertical section partly in elevation as indicated by line 8—8 of Fig. 7.

Fig. 9 is a horizontal sectional view on line 9—9 of Fig. 5, this view being similar to Fig. 7 but showing a different relative positioning of parts.

Fig. 10 is a fragmentary perspective view showing a portion of the operating means for the water valve.

Fig. 11 is an enlarged detail vertical section on line 11—11 of Fig. 3.

The form of construction selected for illustration in the present application may be considered as preferred, with the understanding however that within the scope of the invention as claimed, variations may be made.

The main body of the device includes a base 12 having a central opening 13 through which the plants to be set, may pass, the upper end of said opening being internally shouldered and receiving the lower end of a laterally projecting portion 14 on a plant chute 15, the upper end of said portion 14 being closed by a plate 16 which projects outwardly from said portion 14 and is formed with an opening 17 vertically aligned with the opening 13. Two vertical rods 18 are rigidly secured at their lower ends in any desired manner, to the base 12, said rods passing through openings in the plate 16 and being provided with nuts 19 which tightly hold said plate down, to clamp the lateral

portion 14 of the chute 15, in place. The rods 18 project a considerable distance above the plate 16 and at their upper ends, these rods carry a horizontal plate 20 which may well be secured to the rods by passing the latter through openings and providing them with nuts 21. Plate 20 is formed with a central opening 22 vertically aligned with the openings 13-17, said opening embodying opposed arcuate offsets 23. The intermediate portions of the side edges of the plate 20 are formed with arcuate notches 24 concentric with the opening 22, for a purpose to appear.

A tubular plunger 25 passes slidably through the openings 22 and 17 and is downwardly projectable from the position of Fig. 1, through the opening 13, for the purpose of forming a plant-receiving hole in the earth, as will be clear from Fig. 4. The lower end 26 of this plunger and its upper end 27 are preferably formed separately from the main body portion of said plunger, and said end 26 is downwardly tapered and provided with a downwardly facing valve seat 28. A downwardly opening valve 29 is normally seated against the seat 28 and is downwardly pointed to readily penetrate the earth when the plunger is depressed. A stem 30 rises from the valve 29 within the plunger 25, passes through a stuffing box 31 in the upper end 27 of said plunger, and is provided at its upper end with a cross arm 32 whose ends pass slidably through slots 33 in said plunger end 27. A coiled compression spring 34 in this plunger end 27, normally forces upwardly upon the cross arm 32 to hold the valve 29 closed, so that water may be trapped in the plunger, being supplied thereto through an appropriate hose 25^a leading from a water tank 25^b which the operator of the plant setter may carry with the aid of an appropriate harness or the like 25^c.

When the plunger 25 is so positioned that the arms 32 may pass through the offsets 23 of the opening 22 (see Fig. 7), the plunger 25 may be depressed as in Fig. 4, to form a plant-receiving hole in the earth. Then, by turning the plunger so that the ends of the cross arm 32 will underlie portions of the plate 20 as seen in Fig. 9, the valve stem 30 and the valve 29 will be held against ascent, so that slight lifting of the plunger 25 against the action of the spring 34, will effect opening of the valve to discharge water into the newly formed hole. The valve may be left open for the desired length of time, according to the dryness of the ground and if planting is being done when the ground is damp, the watering features need not be used at all. When it is desired to close the valve 29, the plunger 25 is turned until the cross arm 32 may pass upwardly through the offsets 23, whereupon spring 34 immediately acts to close said valve.

An arched operating handle 35 is provided

for the plunger 25, the ends 36 of this handle being disposed at opposite sides of the plunger and secured to a collar 37 which is fixed to said plunger, said ends 36 being also preferably connected with the upper end of the plunger 25, by a transverse pin 38. These handle ends 36 pass through the notches 24 and limit turning of the plunger in either direction. When these handle ends are in contact with one end of the notches 24, there is no possibility of the cross arm 32 catching on the corresponding end of the offsets 23, upon depression of the plunger, but should the plunger and handle be turned to a sufficient extent toward the other end of the notches 24, said cross arm 32 might catch upon the adjacent ends of said offsets 23. To prevent this, I preferably bevel the ends of the cross arm 32, as shown most clearly at 39 in Figs. 8 and 10.

Radially movable hole-closers 40 are provided for closing the hole formed in the earth, after the plant has been deposited therein. These closers are of spade-like form, with plates 41 for preventing up-throw of the earth, and they are carried by vertical, resilient arms 42, the upper ends of these arms being secured to clamps 43, which are secured upon the rods 18. The lower ends of the arms 42 are received in radial recesses 44 in the periphery of the base 12, and operating levers 45 bearing against the outer sides of said arms, are fulcrumed near their lower ends in these recesses, while the upper ends of said levers diverge from the arms 42. These upper ends of the levers 45 are pivoted at 46 to the lower ends of resilient thrust rods 47 which steeply incline toward the plunger 25 and are secured at their upper ends to slides 48 mounted on the rods 18 above the clamps 43, coiled springs 49 being preferably interposed between said slides and clamps. The slides 48 are rigidly connected with each other by a plate 50 constituting a main operating member for the hole-closers 40, in that depression of this plate causes depression of the thrust rods 47, outward swinging of the upper ends of the levers 45 as in Fig. 6, inward movement of the lower ends of said levers, and consequent inward movement of the hole-closers 40 to operative position, as also seen in Fig. 6.

The plate 50 is formed with a central opening 51 through which the plunger 25 passes slidably, and co-acting means are provided on said plate and plunger for connecting them, so that depression of said plunger may be utilized to depress the plate 50 for the purpose of actuating the hole-closers 40. In the present disclosure, the collar 37 is provided with outstanding lugs 52 and the lower side of the plate 50 is equipped with L-shaped lugs 53. When plunger 25 is in its maximum raised position, as in Fig. 1, turning of said plunger by means of its handle 35,

will engage the lugs 52 with the lugs 53, thus establishing an operating connection between the plunger 25 and the plate 50, so that upon depression of the handle 35, said plate will be depressed to operate the hole-closers 40.

When this is done, the parts assume the relation shown in Fig. 6, from which view it will be seen that the thrust devices 47 spring outwardly, arms 42 spring inwardly and the springs 49 are compressed, so that these combined resilient actions will act in again returning the parts to the hole-closing means and its operating mechanism, to normal position when the device is lifted by handle 35.

The general operation of the device is as follows: Assuming that the various parts stand as shown in Figs. 1 and 3, the device is carried to the point at which a plant is to be set and then by downwardly moving the entire device, the hole-closers 40 are caused to penetrate the earth to the limit dictated by foot plates 12^a with which the base 12 may be provided if desired. By now turning the handle 35 slightly, the lugs 52 are dis-

engaged from the lugs 53. The plunger 25 may now be downwardly forced by means of this handle, so that it passes through the opening 13 and penetrates the earth to form a plant-receiving hole, as will be clear from Fig. 4. Now, if it is desired to discharge a quantity of water into this hole, the handle 35 is manipulated to rotate plunger 25 sufficiently to dispose the cross arm 32 under portions of the plate 20 as seen in Fig. 9, whereupon a slight upward pull upon the handle while holding the body of the device down with the foot plates 12^a, will effect opening of the valve 29 as shown in Fig. 5, allowing discharge of water from the tubular plunger.

When the desired amount of water has been fed to the hole, turning of the handle 35 so that the cross arm 32 is receivable in the offset 23, will immediately effect closing of the valve 29. Then, the plunger 25 is raised by means of the handle 35, the lugs 52—53 are inter-engaged with each other, and a plant is dropped down the chute 15, into the hole. This having been done, handle 35 is again depressed and as the plunger 25 is then connected with the plate 50 by means of the lugs 52—53, this plate is depressed to cause inward forcing of the hole-closers 40, by means of the parts 43, 47, 45. The inward movement of the closers 40, serves to force earth from the sides of the hole, inwardly around the roots of the plant so that the latter is securely set. Upon return of the handle 35 to its normal position, the resiliency of the arms 42 serves to again outwardly move the hole-closers 40. The entire device is now in readiness for movement to the point at which the next plant is to be set, with the lugs 52—53 still in engagement with each other, in readiness to act as before.

It will be seen from the foregoing that

unique provision has been made for carrying out the objects of the invention and attention is again invited to the fact that within the scope of the invention as claimed, variations may be made.

70

I claim:—

1. In a plant setter, a body, hole-forming means and hole-closing means carried by said body, and operating means embodying a single handle operable in two ways, to actuate said hole-forming means and said hole-closing means respectively.

75

2. In a plant setter, a body, hole-forming and hole-closing means both mounted for movement with respect to said body, and actuating means for both of the aforesaid means, said actuating means having a common handle mounted for movement in two ways with respect to said body, said operating means having portions for utilizing one movement of said handle for operating said hole-forming means and the other movement of said handle for actuating said hole-closing means.

80

3. In a plant setter, a body, hole-forming means and water-releasing means both mounted for movement with respect to said body, and actuating means for both of the aforesaid means, said actuating means having a common handle mounted for movement in two ways with respect to said body, said operating means having portions for utilizing one movement of said handle for actuating said hole-forming means and the other movement of said handle for actuating said water-releasing means.

95

4. In a plant setter, a body, hole-forming means, water-releasing means and hole-closing means all mounted for movement with respect to said body, and actuating means for all of the aforesaid means, said actuating means having a common handle mounted for movement in three ways with respect to said body, said operating means having portions for utilizing one movement of said handle for actuating said hole-forming means, for utilizing another movement of said handle for actuating said water-releasing means and for utilizing the third movement of said handle for actuating said hole-closing means.

105

5. A plant setter comprising a body having an opening, a hand-depressed plunger slidably carried by said body and movable through said opening to form a plant-receiving hole in the earth, hole-closing means mounted on said body, operating means for said hole-closing means, and means for operatively connecting said operating means with said plunger to be actuated by the latter.

110

6. A plant setter comprising a body having an opening, a hand-depressed plunger slidably carried by said body and movable through said opening to form a plant-receiving hole in the earth, hole-closing means

115

120

125

130

mounted on said body, operating means for said hole-closing means embodying a main operating member near said plunger and mounted for vertical movement, and means for connecting said plunger with said member, whereby the former may be utilized to actuate the latter.

7. A plant setter comprising a body having an opening, a hand-depressed plunger 10 slidably carried by said body and movable through said opening to form a plant-receiving hole in the earth, hole-closing means mounted on said body, operating means for said hole-closing means embodying a main 15 operating member near said plunger and mounted for vertical movement, and means operable upon rotation of said plunger for connecting the latter with said member, whereby the plunger may be utilized to actuate said member.

8. A plant setter comprising a base having an opening, a plunger slidable through said opening to form a plant-receiving hole in the earth, rods rising rigidly from said 25 base, radially movable hole-closers at the lower side of said base having carrying arms connected to said rods, levers fulcrumed on the base for inwardly forcing said hole-closers when the upper ends of said levers 30 are moved outwardly, vertically disposed thrust members connected at their lower ends with said levers for so moving them, an operating member through which the plunger is slidable, said operating member being connected to the upper ends of said 35 thrust devices for downwardly moving them to actuate said levers, and means for connecting said member with said plunger, whereby the latter may be utilized to actuate said member.

9. A plant setter comprising a base having an opening, a plunger slidable through said opening to form a plant-receiving hole in the earth, rods rising rigidly from said 45 base, radially movable hole-closers at the lower side of said base having carrying arms to said rods, levers fulcrumed on the base for inwardly forcing said hole-closers when the upper ends of said levers are moved 50 outwardly, vertically disposed thrust members connected at their lower ends with said levers for so moving them, an operating member through which said plunger is slidable, said operating member being connected to the upper ends of said thrust devices, and means operable upon rotation of said plunger for connecting the latter with said member, whereby said plunger may be utilized to downwardly force said member and said 55 thrust devices to actuate said levers.

10. A plant setter comprising a body, a water-containing plunger carried slidably by said body for forming a plant-receiving hole in the earth, said plunger having a water discharge orifice at its lower end and a valve for

normally preventing discharge of water through said orifice, and means operable by predetermined movement of said plunger with respect to said body for opening said valve.

11. A plant setter comprising a body, a water-containing plunger carried slidably by said body for forming a plant-receiving hole in the earth, said plunger having a water discharge orifice at its lower end and a downwardly opening valve normally preventing discharge of water through said orifice, a stem rising from said rod and having a laterally projecting actuator, and means on said body capable of striking said actuator upon raising of the plunger, to effect valve opening.

12. A structure as specified in claim 11; said plunger being rotatable to dispose said means and said projection either in or out of co-operable relation.

13. A plant setter comprising a base having an opening, a water-containing plunger projectable through said opening to form a plant-receiving hole in the earth, said plunger having a water discharge orifice at its lower end, a downwardly opening valve normally preventing discharge of water through said orifice, a stem rising from said valve and having an actuator extending laterally beyond the plunger, a rod rising rigidly from said base, and a member carried by said rod capable of striking said actuator upon ascent of said plunger, to effect valve opening.

14. A structure as specified in claim 13; said plunger being rotatable to bring said member and said projection either into or out of co-operable relation with each other.

15. A plant setter comprising a base having an opening and a plant chute leading thereto, a water-containing plunger slidable through said opening for forming a plant-receiving hole in the earth, said plunger having a water discharge orifice at its lower end and a downwardly opening valve normally preventing discharge of water through said orifice, a valve-opening device at the periphery of said plunger and operatively connected with said valve for opening the latter when said device is held and the plunger raised, hole closers carried by the base in outwardly spaced relation with said opening, rods rising rigidly from the aforesaid base, a plate carried rigidly by the upper ends of said rods and having an opening through which said plunger and said valve-opening device are slidable, said plate having a portion to hold said device against ascent when the plunger is rotated to engage said device with said plate portion, a member slidable on said rods, operating connections between said member and said hole closers for operating the latter upon vertical movement of said member, and means operable by rotation of said plunger for connecting it with said member, whereby vertical movement of

10 16. In a plant setter, a base having an opening through which a plant may pass, a plant chute having a lateral enlargement at its lower end registering with the upper end of said opening, a plate closing the upper end of said enlargement and having an opening aligned with the aforesaid opening, the plate, base and enlargement being secured against relative movement, and a plunger 15 slideable in the opening of said plate and projectable through the opening of said base to form a plant-receiving hole in the earth.

15 17. In a plantsetter, a body, a radially movable hole closer carried by said body, a lever fulcrumed on said body for operating said closer when the upper end of said lever is moved outwardly, a resilient thrust device 20 pivoted at its lower end to the upper end of said lever and inclined inwardly therefrom, a downwardly movable member to which the upper end of said thrust device is secured, and means for vertically guiding said member.

25 18. In a plant setter, a body, a tubular water-containing plunger slidably mounted on said body, a pointed hole former on the lower end of said plunger, said plunger being provided with an operating handle by means 30 of which it may be slid and turned, hole-closing means movably mounted on said body and operating means for said hole-closing means embodying a vertically movable member adjacent the plunger and means on said plunger 35 for connecting the latter with said vertically movable member upon predetermined turning of said plunger.

40 19. In a plant setter, a body, a tubular water-containing plunger slidably mounted on said body, a pointed hole former on the lower end of said plunger provided with a water-releasing valve, a handle secured to the upper end of said plunger for sliding the latter, and opening means for said valve embodying co-operable parts on said plunger 45 and said body adapted to open the valve upon ascent of the plunger after the hole-forming operation.

50 20. In a plant setter, a body, a tubular water-containing plunger slidably mounted on said body, a pointed hole former on the lower end of said plunger provided with a water-releasing valve, a handle secured to the upper end of said plunger for sliding and turning the same, opening means for said valve embodying co-operable parts on said plunger and said body adapted to open the valve upon ascent of the plunger after the 55 hole-forming operation, hole-closing means movably mounted on said body, and operating means for said hole-closing means embodying a vertically movable member adjacent the plunger and means on said plunger 60 for connecting the latter with said vertically

movable member upon predetermined turning of said plunger.

65 21. In a plant setter a tubular handle equipped water-containing plunger, a pointed hole former on the lower end of said plunger 70 having a water discharge port, an upwardly closing water-releasing valve for said port having a pointed lower end at the extreme point of said hole former and co-operable with the latter in the hole-forming operation, and means rising from said valve 75 for effecting opening thereof after the hole-forming operation.

In testimony whereof I have hereunto affixed my signature.

LEWIS A. ETCHISON.
